UNITED STATES PATENT OFFICE.

IRA FINGERMAN, OF CHICAGO, ILLINOIS, ASSIGNOR TO UNIVERSAL LEATHER GOODS CO., OF CHICAGO, ILLINOIS, A CORPORATION OF ILLINOIS.

DESIGN FOR A VANITY BOX.

Application filed October 24, 1925. Serial No. 15,242. Term of patent 14 years.

To all whom it may concern:

Be it known that I, IRA FINGERMAN, a citizen of the United States, and a resident of the city of Chicago, county of Cook, and State of Illinois, have invented a new, original, and ornamental Design for Vanity Boxes, of which the following is a specification, reference being had to the accompanying drawing, forming a part thereof, and in which—

Fig. 1 is a plan view of a vanity box, showing my new design; and

Fig. 2 is a front elevational view thereof.

I claim:

The ornamental design for a vanity box, as shown.

IRA FINGERMAN.
